UNITED STATES PATENT OFFICE.

SAMUEL E. SPERRY, OF NEW YORK, N. Y., ASSIGNOR TO INTERNATIONAL TYPESETTING MACHINE COMPANY, OF NEW YORK, N. Y., A CORPORATION OF NEW YORK.

SLUG-EJECTING DEVICE FOR LINE-CASTING MACHINES.

1,123,814.

Specification of Letters Patent. Patented Jan. 5, 1915.

Application filed June 27, 1912. Serial No. 706,189.

To all whom it may concern:

Be it known that I, SAMUEL E. SPERRY, a citizen of the United States, and resident of Woodhaven, borough of Queens, county of 5 Queens, city and State of New York, have invented certain new and useful Improvements in Slug-Ejecting Devices for Line-Casting Machines, of which the following is a specification.

10. This invention relates to improvements in machines in which printing slugs are cast in a suitable mold and are delivered or discharged therefrom by means of an ejector which is adapted to be advanced from the 15 rear through the mold and to engage the printing slug or bar on its bottom edge. In machines of this type the molds are adjustable in length to produce printing bars for printing columns or pages of different 20 widths.

One of the main objects of the invention is to provide an ejector mechanism by means of which a solid or one-piece ejector blade will be provided for each length of slug or 25 type bar, and to provide simple and efficient means by means of which the ejector blade of the proper width may be brought into register with the line mold and into co-operative relation with a horizontally reciprocating slide or pusher bar.

Another object of the invention is to provide a series of ejector blades arranged in parallel relation and of different widths and to so mount said series of blades that they 35 may be readily shifted transversely to the line of movement of the main slide or pusher bar to bring the selected ejector blade into co-operative relation with said slide and in register with the line mold.

40. A further object of the invention is to provide a series of ejector blades of different widths, and means whereby the ejector of the desired width may be selected and brought into register with the line mold and 45 into co-operative relation with the ejector blade operating mechanism.

There are other important objects and advantages of the invention which will appear hereinafter.

50. In the drawings, Figure 1 is a sectional view showing a portion of the ordinary mold wheel, knife block, mold slide, and operating parts, of a linotype machine of the Mergenthaler type, showing my inven-

tion applied thereto; Fig. 2 a sectional view 55 on the line II—II of Fig. 1, looking in the direction of the arrows; Fig. 3 a detail plan view of the ejector blade case and the means for shifting it laterally; Fig. 4 a front view of the ejector blade case and its shifting 60 frame; and Fig. 5 a side elevation thereof. Fig. 6 is a side elevation of the main slide and one ejector blade connected therewith.

Referring to the various parts by numerals, 1 designates the mold wheel or carrier 65 having the usual slot 2 which receives the mold 3.

4 designates the knife block which is arranged in front of the mold and carries the usual slug trimming knives 5.

6 designates the usual main slide or guide in which the usual ejector blade of the ordinary Mergenthaler linotype machine is guided in its slug ejecting movements.

70 In the main slide or guide is arranged an 75 ejector blade case 7, said case consisting of the upper and lower plates 8 and the side plates 9, the front of said case being open, as indicated clearly in Fig. 4. In this case are arranged a number of ejector blades 10, 80 said blades being of different widths and corresponding to the variations in the lengths of type bars or slugs which the machine is adapted to cast. These ejector blades are arranged close together in par-

85 allel relation and in regularly increasing widths, so that the smallest or narrowest ejector blade lies against one side plate 9 and the largest or widest ejector blade lies against the other side plate 9, as indicated 90 clearly in Fig. 4 of the drawing.

To hold the free forward ends of the ejector blades in their proper relative positions and to guide them in their reciprocating movements, a stepped filler piece 10^a is secured 95 in the forward end of the ejector blade case. It will be noted that this stepped filler piece engages the upper edge of each ejector blade at the forward end thereof when the blades are in their normal retracted position, and that it forms a guide for said blade and prevents its forward end lifting or moving upwardly, so that the ejector will be accurately guided to the mold. The top and bottom plates 8 of the ejector blade case 100 are each provided with a pair of parallel, transversely arranged, oblique grooves 11, as shown clearly in Fig. 3. The forward

end of this case is open and said case is adjustable or movable backwardly in the main slide or guide to bring any one of the ejector blades into register with the mold opening so that the selected ejector may be moved through the mold to eject the slug. As a simple means for accomplishing this sidewise adjustment or movement of the ejector blade case, I provide a reciprocating frame 12, the upper and lower bars 13 of which extend over the bars 8 of the ejector case. The bars 13 of the shifting frame are each provided with two projections 14 which enter the slots 11 of the adjoining bar of the ejector case. Each of these bars 13 is also provided with a long vertical rib 15 which fits and slides in a corresponding groove 16 in the upper and lower walls of the main guide 6. It is manifest that by moving the shifting frame 12 forwardly and rearwardly the ejector case will be moved laterally through the medium of the projections 14 and the cam slots 11 in which they fit.

To move the ejector case I connect to the shifting frame a lever 17 and provide means for locking said lever in its various positions, said means consisting of the bracket 18 having a series of holes therein and a locking pin 19 adapted to be passed through the lever in any one of said series of holes. By moving the lever the ejector blade of the proper width may be brought into register with the mold opening and may be then locked by inserting the pin 19 through the lever and the registering hole in the bracket 18.

To operate the ejector blades I provide the main slide or push bar 20 which is operated by means of the usual pitman 21 connected to the head block 22. The forward end of the main slide or push bar enters the rear end of the ejector blade case and is provided at its lower edge with an upturned hook 23. This main slide or push bar is of the same thickness as the ejector blades, and each ejector blade at its rear lower corner is provided with a slot or recess 24 of the same shape as the hook 23 of the main push bar. These slots or recesses are so arranged that they register with the coöperating hook on the main slide. The main slide or push bar is directly in line with the mold slot and is maintained permanently in that relation. By shifting the ejector blade case or holder laterally through the medium of a lever 17 the desired ejector blade is brought into line with the main slide so that the hook 23 on said slide fits in the recess 24 of a selected blade. The selected blade and the main slide are then interlocked in operative relation, the interlocked blade being directly in line with the slot in the mold. It is manifest, therefore, that by forcing forward the main slide the ejector blade is carried forward to force out the cast slug or type bar,

as indicated in dotted lines at 25 in Fig. 1. When the main slide is returned to its normal position the ejector blade is returned to its normal position within the ejector blade case by reason of the hook 23 being interlocked in the recess 24 of the blade. 70

The bar 26 serves as a guide for the push bar 20 and also closes the inner end of the ejector blade case when the same is thrown laterally out of the frame 12 by the lever 17. It is manifest that this case must be open at its inner end to receive the main slide 20. 75

The advantage of having a solid or one-piece ejector blade is manifest. Its operation is positive and accurate and it is practically impossible for the mechanism to become jammed or inoperative. It is to be understood, of course, that the ejector blades are thin so that a suitable number of them 80 may be arranged within the ejector blade case without making the case too thick to be conveniently arranged within the main guide. It is also manifest that the lateral or sidewise movement of the ejector case 85 need be very slight, and yet permit of the use of a considerable number of ejector blades. 90

It is, of course, to be understood that the means for laterally shifting the ejector case 95 may be varied, and I do not wish to be limited in this respect.

What I claim is:

1. In a linotype machine, the combination with a mold and a guide arranged adjacent thereto, a main slide adapted to reciprocate in said guide, a series of independently operable ejector blades of different widths, and means for bringing one of said series of blades into register with the mold and into operative relation with the main slide. 100

2. In a linotype machine, the combination with a mold, a main guide, a series of ejector blades, means for moving said series of blades laterally to bring a selected blade 110 into register with the mold, and means for reciprocating said selected blade to eject a cast slug from the mold.

3. In a linotype machine, the combination with a mold, a main guide, a series of ejector blades of different widths, means for moving said series of blades laterally to bring a selected blade into register with the mold, and means for reciprocating said selected blade to eject a cast slug from the mold. 115

4. In a linotype machine, the combination of a mold, a main guide, a reciprocating slide therein, a series of ejector blades of different widths arranged side by side in parallel relation, means for laterally shifting said series of blades to bring any selected blade into coöperative relation with the main slide and into register with the mold. 125

5. In a linotype machine, the combination 130

of a mold, a main guide, a reciprocating slide therein, a series of ejector blades of different widths arranged side by side in parallel relation, means for laterally shifting said series of blades to bring any selected blade into co-operative relation with the main slide and into register with the mold, and means for locking said series of blades in position with respect to the main slide and to prevent lateral movement thereof.

6. In a linotype machine, the combination of a mold, a main slide, a main guide therefor, an ejector case within said main guide, a series of ejector blades in said case, said blades being of different widths, means for shifting said ejector case laterally to bring a selected ejector into co-operative relation with the main slide and in register with the mold.

7. In a linotype machine, the combination of a mold, a main slide, a main guide therefor, an ejector case within said main guide, a series of ejector blades in said case, said blades being of different widths, means for shifting said ejector case laterally to bring a selected ejector into co-operative relation with the main slide and in register with the mold, and means on the main slide for engaging the selected ejector whereby the selected ejector blade will reciprocate with the main slide.

8. In a linotype machine, the combination of a mold, a main guide, a main slide therein in line with the mold, an ejector case in said main guide, a series of ejector blades in said case of different widths and arranged side by side in parallel relation, a reciprocating frame, means whereby the reciprocation of said frame will shift the ejector case laterally to bring a selected blade into line with the mold and the slide, and means carried by the main slide for engaging each selected ejector blade as the ejector case is shifted laterally.

9. A main slide, a series of ejector blades of different widths arranged therein, a main ejector bar and means for shifting said blades laterally to bring any selected blade into co-operative relation with the main ejector bar.

10. A main slide, a series of ejector blades of different widths arranged therein, a main ejector bar, means for shifting said blades laterally to bring any selected blade into co-

operative relation with the main ejector bar, and means for interlocking the selected ejector blade with the main ejector bar for reciprocation therewith.

11. In a linotype machine, the combination of a mold, a series of ejector blades of different widths near said mold, and means for operating any one of said blades independently of all the other blades of the series to eject a cast slug from said mold.

12. In a linotype machine, the combination of a mold, a series of ejector blades of different widths near said mold, means for bringing any one of said blades into register with said mold and means for operating said blade independently of all the other blades of the series to eject a cast slug from said mold.

13. In a linotype machine the combination of a mold, a series of independently operable ejector blades of different widths, means for selecting any one of said blades, and means for operating the selected blade to eject a cast slug from said mold.

14. In a linotype machine the combination of a mold, a series of independently operable ejector blades of different widths, a blade moving means, and means for selecting any one of said blades and connecting it to the blade operating means.

15. In a linotype machine the combination of a mold, a series of ejector blades, means for selecting any one of said blades and means for operating the selected blade independently of all the other blades of the series.

16. An ejector mechanism for typographical machines comprising a series of ejector blades of different sizes and adjustable at will to bring one or another of them into operative position.

17. An ejector mechanism for typographical machines comprising, in combination, a series of ejector blades of different sizes, a frame in which said blades are slidably arranged, and an actuating device, the said frame being movable to bring one or another of the blades into position to be operated by the said device.

In testimony whereof I hereunto affix my signature in the presence of two witnesses.

SAMUEL E. SPERRY.
